HOLDER FOR SEWING ARTICLES

Mary Pietrowiak, 1304 Maple Ave., Baltimore, Md.

Filed Dec. 3, 1964, Ser. No. 82,897

Term of patent 14 years

(Cl. D3—19)

FIG. 1

FIG. 3

FIG. 2

FIGURE 1 is an assembled perspective view of my new design for a holder for sewing articles;

FIGURE 2 is a perspective view similar to that of FIGURE 1 but with the cover portion removed and placed alongside the rotatable holder for sewing articles; and

FIGURE 3 is a vertical central section through the lower part of the assembled holder for sewing articles shown in FIGURE 1 which shows the cover seated in the annular groove of the base and the rotatable aspect of the holder for sewing articles on the base.

The side opposite that shown in FIGURES 1 and 2 is exactly the same as shown by reason of circular symmetry of the holder for sewing articles.

The essential features of my design reside in the full line portions on the drawing. The broken line showings

of the various sewing implements are for purposes of illustration only.

I claim:

The ornamental design for a holder for sewing articles, as shown and described.
